CLAIM

The ornamental design for a grill handle towel bar assembly, as shown and described.

DESCRIPTION

FIG. 1 is a front, left perspective view of my new design for a grill handle towel bar assembly shown in a grilling environment;

FIG. 2 is a top, right perspective view of the grill handle towel bar assembly of FIG. 1;

FIG. 3 is a front elevation view thereof;

FIG. 4 is a rear elevation view thereof;

FIG. 5 is a top plan view thereof;

FIG. 6 is a bottom plan view thereof;

FIG. 7 is a left side elevation view thereof;

FIG. 8 is a right side elevation view thereof; and,

FIG. 9 is a top, front, left perspective exploded view thereof.

The broken lines in the drawings depict environmental subject matter only and form no part of the claimed design.

1 Claim, 6 Drawing Sheets

Matter enclosed in heavy brackets [ ] appears in the original patent but forms no part of this reissue; matter printed in italics indicates the additions made by reissue.
